UNITED STATES PATENT OFFICE.

CHARLES E. BARDWELL, OF HOLYOKE, MASSACHUSETTS.

DESIGN FOR A BOWL.

SPECIFICATION forming part of Design No. 31,737, dated October 31, 1899.

Application filed July 3, 1899. Serial No. 722,765. Term of patent 14 years.

To all whom it may concern:

Be it known that I, CHARLES E. BARDWELL, a citizen of the United States of America, residing at Holyoke, in the county of Hampden and State of Massachusetts, have invented and produced a new and original Design for Bowls, of which the following is a specification, reference being had to the accompanying drawing, forming part thereof.

10 The figure in the drawing forming part of this specification is a perspective view of a bowl embodying my complete design.

As shown in the drawing, the leading feature of my design consists in the bowl-shaped body A, supported on the base B, said bowl having formed centrally within it a hollow

cylinder E, projecting vertically from the bottom of the bowl and reaching nearly to the top thereof, which cylinder is perforated at different points F, as shown. The outer edge 20 of the base B is provided with an upturned edge C, whereby an annular depression D will be formed therein.

Having described my invention, what I claim as new, and desire to secure by Letters 25 Patent, is—

The design for a bowl, as herein shown and described.

CHARLES E. BARDWELL.
